UNITED STATES PATENT OFFICE.

THADDEUS HYATT, OF NEW YORK, N. Y., ASSIGNOR TO ELIZABETH ADELAIDE LAKE HYATT, OF SAME PLACE.

CONSTRUCTING AND REPAIRING ILLUMINATING-ROOFS, &c.

SPECIFICATION forming part of Letters Patent No. 257,712, dated May 9, 1882.

Application filed April 14, 1882. (No model.)

To all whom it may concern:

Be it known that I, THADDEUS HYATT, a citizen of the United States, and a resident of the city, county, and State of New York, have invented certain new and useful Improvements in Constructing and Repairing Illuminating-Roofs and Roof-Pavements, of which the following is a specification.

In the drawings attached hereto and making part of this specification, like letters refer to like parts in all the figures.

Figure 1 represents a foundation-grating, the openings of which are meant to be each about one foot square. A, the grating; a, main bars at the sides of the grating; a', intermediate main bars; b, cross-bars at the ends of the grating; b', intermediate cross-bars; c, lugs cast upon the under side of the main side bar, a, to underlap and give support to the abutting cross-bars of an adjoining grating, Fig. 1 being an end or starting grating.

Fig. 2 represents a foundation-grating, A', made to match A, Fig. 1, and formed with an open side of abutting cross-bars designed to be supported at their ends upon the underlapping lugs c of the adjoining grating A.

Fig. 3 represents the two gratings A and A' united, and illustrates the invention of grating A formed with the lugs c, in combination with grating A' formed with an open side of abutting cross-bars, the result being a combined grating, A A', having the appearance of a single casting, the line of dead material a'' a'', where the two gratings meet, being no thicker than the intermediate parallel bars, a' a', of the gratings.

Fig. 4 represents several features of the invention, viz: first, in the form of a curved foundation-grating for making rear-extension roofs; second, as a foundation-grating formed with ventilating-scuttles, and, third, as a concreted foundation-grating. B shows the ventilating-scuttles; d, curbs around the scuttles; e, hinged cover to scuttle; the dotted surface indicates concrete. C, concrete illuminating-gratings or quarry glass holders cemented to the foundation-grating by a bond of hydraulic cement.

Fig. 5 represents a foundation-grating cast in stoop and step shape for making illuminating-area-coverings.

Fig. 6 represents a hand-size illuminating-grating or quarry glass holder designed for closing the openings of foundation-gratings in constructing illuminating rear-extension roofs and area-coverings, the quarry being formed with no dead material at the borders, the sides of the glasses D being bare at those points.

Fig. 7 represents a concrete quarry glass holder formed with no dead border.

Fig. 8 represents a quarry set with glasses formed with shoulders that rise above the face of the quarry. D shows the glasses; g, shoulders or surplusage of the glasses shown in Fig. 9.

Fig. 9 is a cross-section of Fig. 8, designed to show the necks or surplusage of the glasses D, one of the glasses being shown by itself.

Fig. 10 represents a foundation-grating, two of the openings of which are closed by quarries set with shouldered glasses. The dotted surface of the construction represents a facing of concrete put between the shoulders of the glasses and over the grating.

The object of my invention is to make patent light-work not liable to leak, to prevent sweating, to obtain ventilation by simple and inexpensive means, and to make the work handsomer and cheaper than heretofore.

Figs. 1, 2, 3, and 6 illustrate the essential features of my invention as a new system of illuminating construction.

The main feature of the system consists in employing two sets of gratings, one within the other, for the construction of illuminating-roofs and roof-pavements, the larger gratings representing the mechanical strength of the roof or pavement, and taking the place of the rafters or supporting-bars of the old construction, and the smaller gratings (being the glass-carriers) representing the weather-surface of the constructions. The larger gratings I call "foundation-gratings," and the smaller gratings I call "illuminating-quarries." The most prominent feature of the system as a result of the double-grating construction is its monomorphous character. This feature is illustrated by Figs. 3 and 9, where a number of glass-set quarries are combined with foundation-gratings in a way to make the construction appear like a single casting.

The new features of the foundation gratings

and quarries which make possible the monomorphous character are the improvements in the mode of constructing the hand-size gratings shown by Fig. 6, where the quarry is made 5 with no dead material at the borders, and by Fig. 8, where the glasses are formed with shoulders or necks that rise about half an inch above the face of the quarry, in combination with foundation-gratings constructed as shown by 10 Figs. 1, 2, 3. The effect of making glass-holding quarries without borders, as illustrated by Fig. 6, is to produce an equality of dead lines throughout the entire construction, no matter how many quarries are employed, because the 15 bare sides of the glasses become in the combination cemented equally to the bars of the foundation-gratings, to this extent causing the foundation-gratings to become also the carriers of the glasses, so that when the bars of the foundation-gratings are made no thicker than the bars of the quarries between the glasses the whole work seems like one piece. Illuminating-surfaces of naked iron and glass may in this way be made of any size and of a perfect 25 monomorphous character.

In the illustrations I have given I have represented the glasses as square and the lines as straight; but the principle of construction applies equally to circular and other shaped 30 glasses, and to curved as well as straight lines.

Figs. 8 and 9 are designed to not only illustrate a method of making monomorphous concrete lights and illuminating constructions, but to also illustrate my invention of improvements 35 in repairing old work.

The invention consists substantially in setting an iron grating with glasses made of a depth so great as to rise above the level of the glass-holders sufficiently to become the means 40 of fastening to the face of the grating a facing body of hydraulic cement or concrete.

Figs. 8 and 9 represent new work and show the glasses formed with the neck *g*. The quarries are made as shown by Fig. 8, and when 45 set in the foundation-grating, as shown by Fig. 9, a monomorphous finishing-coat of Portland cement, pure or with aggregates, is put over the face of the work and "floated" to the level or tops of the glasses, as represented by the dotted surface of Fig. 9.

Where the work is repairing I knock out all the old glasses of the construction, whether top roof or area covering, and replace them with glasses of greater depth, the new glasses 55 being deep enough to rise above the face of the metal gratings sufficiently to hold and fix the facing of cement or concrete put between the glasses as described, and as illustrated by Fig. 9.

Fig. 4 represents three new features (and important ones) connected with the construction of illuminating-roofs over the rear extensions of the principal stories of buildings—viz., ventilation, prevention of sweating, and prevention of leakage. The curved form of the 60 foundation-gratings establishes the curved

form of the roof, and makes unnecessary a curved illuminating-grating or glass-holder. These roofs as made commonly are formed of curved glass-holders, the "illuminating-tiles" 70 used for such work being the actual roof. In my new construction the gratings that carry the glasses, being of hand size or quarries, may be entirely flat without destroying the curved appearance of the roof. Hence in these constructions the curved foundation-gratings form a part of my improvements in illuminating-roofs. Ventilation is effected in these roofs by means of the ventilating-scuttles shown in Fig. 4. The lower half of the grating is represented 80 with a coating of concrete to show my invention of curved concreted illuminating rear extension-roofs. In the construction of such roofs I first incrust each separate grating with concrete, the same being done in suitable 85 molds. These concreted gratings are then brought to the building and placed in position, and the illuminating-quarries, also made of concrete and glass, are cemented within the openings of the grating-foundation. The surfaces 90 of both the foundation-gratings and the quarries being concrete, a mortar or grout of hydraulic cement makes a bond between the two as water-tight and perfect as the bond between two bricks. The iron of the construction being 95 all embedded in concrete, no "sweating" takes place. For the same reason no expansions and contractions take place, and by consequence no leakages from expansions and contractions. This roof construction I desire to distinguish 100 from my former inventions where the roofs are made of concreted glass-holding gratings combined with rafters. In the construction hereinabove described my improvement consists in combining glass-holding quarry gratings 105 with concreted foundation-gratings.

Fig. 5 represents a new mode of constructing illuminating-grating stoop and step roofs over sunk areas. As ordinarily made these roofs are formed of flat illuminating-gratings 110 bolted to "string-pieces," the form of the stoop and steps being determined by the form of the string-pieces; but by my new method, as illustrated by Fig. 5, the stoop and step form is obtained in the foundation-grating itself, 115 which is cast in one piece, as shown in the figure, the openings being closed either with glass plates or with illuminating-quarries after the foundation-gratings have been placed in position.

Having thus fully and clearly described my invention, what I claim and desire to secure by Letters Patent, is—

1. Illuminating-roofs and roof-pavements made by combining quarry glass holders with foundation-gratings, substantially as and for the purposes herein set forth and illustrated.

2. Monomorphous illuminating-roofs and roof-pavements constructed substantially as and for the purposes herein set forth and illustrated.

3. Illuminating-roofs made by combining

illuminating-quarries with curved foundation-gratings, substantially as and for the purposes herein set forth and illustrated.

4. Illuminating area-coverings formed by combining illuminating-quarries with foundation-gratings cast in stoop and step form, substantially as and for the purposes herein set forth and illustrated.

5. Illuminating area-gratings cast in stoop and step form and combined with glass, substantially as and for the purposes herein set forth and illustrated.

6. Foundation-gratings cast or formed with ventilating-scuttles, substantially as and for the purposes herein set forth and illustrated.

7. Concreted foundation-gratings, in combination with either concrete or concreted illuminating-quarries, substantially as and for the purposes herein set forth and illustrated.

8. Foundation-gratings cast with underlapping lugs, substantially as and for the purposes herein set forth and illustrated.

9. Foundation-gratings formed with an open side of abutting cross-bars, in combination with foundation-gratings made with underlap-

ping lugs to give support thereto, substantially as and for the purposes herein set forth and illustrated.

10. Illuminating-gratings formed with no dead material at the borders, substantially as and for the purposes herein set forth and illustrated.

11. Facing illuminating-roofs and roof-pavements with concrete or material held to the face of the grating by means of necks or glass surplusage, substantially as and for the purposes herein set forth and illustrated.

12. Illuminating-roofs and roof-pavements made by combinations of illuminating-gratings or of quarry glass holders, the glasses of which are formed with glass surplusage or necks to stand above the general level of the work as a means of attachment for a monomorphous finishing-coat of material, substantially as and for the purposes herein set forth and illustrated.

THADDEUS HYATT.
